RAILWAY SIGNALING APPARATUS

Filed Dec. 11, 1946

UNITED STATES PATENT OFFICE

2,482,296

RAILWAY SIGNALING APPARATUS

Charles B. Shields, Penn Township, Allegheny County, Pa., assignor to The Union Switch & Signal Company, Swissvale, Pa., a corporation of Pennsylvania

Application December 11, 1946, Serial No. 715,460

9 Claims. (Cl. 246—130)

1

My invention relates to railway signaling apparatus and particularly to the organization of such apparatus into coded track circuit systems of railway signaling incorporating approach control means.

Coded track circuit systems of railway signaling have been proposed in order to obtain the improved shunting characteristics and protection against broken rails and foreign current that coded track circuits afford in comparison with the usual steadily energized track circuits. Additional advantages are obtained from the use of coded track circuits by employing a plurality of code rates to provide a plurality of channels for communication through the track rails, thereby making it unnecessary to use line wires extending between the ends of a track section, and by employing coded alternating current in the track rails which enables control to be established over either or both train carried apparatus and wayside equipment.

In these systems maximum advantage is obtained from the use of coded track circuits by applying the coded track circuit energy to the exit end of each track section for transmission through the track rails to the entrance end where it is used to operate decoding apparatus at that end. The decoding apparatus is utilized for the control of wayside signals and for the control of the track circuit energy that is applied to the section in the rear. Entrance of a train into a section therefore causes a control to be established at the entrance end of the section by means which utilize the track rails as transmission conductors and make unnecessary the use of control line wires.

In many cases it is necessary to have traffic in a section establish a control at a point in advance of the entering end of the section. This is particularly true, for example, in the case of a highway crossing signal located at a grade intersection intermediate the ends of a section. Operation of such a signal must be initiated when the train enters the control section for the signal and must be terminated when the train clears the intersection. In coded track circuit systems where cab signaling is involved it is necessary to detect the unoccupied condition of the control section by means of track circuit energy which will not cause operation of the cab signals, and in such cases it has been customary to use steady or non-coded direct current for detecting the clearing of the control section.

It is an object of my invention to provide novel and improved means for detecting the clearing

2

of a control section for a highway crossing signal in a coded track circuit system of railway signaling.

Another object is to provide novel and improved means for utilizing coded track circuit current for detecting the clearing of a control section for a highway crossing signal in a stretch of track provided with a coded track circuit system of railway signaling.

10 Another object of my invention is to provide novel and improved means for utilizing coded direct current in a control section for a highway crossing signal in a coded track circuit system of railway signaling, and for applying coded alternating current to such section when required for controlling cab signals in such control section.

15 Another object is to provide novel and improved means for controlling a highway crossing signal in a coded track circuit system of railway signaling.

20 In accordance with my invention the control section for a highway crossing signal is normally supplied with coded track circuit current of the clearing-out type, and the wayside equipment at 25 the entering end of the section as well as the highway crossing signal at the intersection are controlled by means of a line circuit incorporating contacts at the ends of the circuit synchronously operated to provide two control channels for respectively controlling apparatus at the entering end, and apparatus at the intersection. The line wire controlled apparatus at the intersection also provides means for applying coded alternating current to the control section during the interval that a train approaches the intersection in the control section.

25 I shall describe one form of apparatus embodying my invention and shall then point out the novel features thereof in claims.

30 40 The accompanying drawing is a diagrammatic view of a preferred form of apparatus embodying my invention.

45 Referring to the drawing, the reference characters 1 and 1a designate the track rails of a stretch of railway track in which traffic equipped with train carried signaling or control facilities operates in the direction indicated by an arrow, or from left to right as viewed in the drawing. The rails 1 and 1a are divided by means of insulated joints 2 into a track section 3—4, and the section is further divided by joints 2 at cut-section location 3a into adjoining rear and advance subsections 3—3a and 3a—4, respectively. The rear subsection 3—3a is intersected at grade by a highway H at its exit end.

The reference character XS designates a highway crossing protective device located at the intersection for warning highway traffic of the approach of a train to the crossing. The device XS may take any suitable form, such as flashing lights, wigwag, crossing gate, etc., but for the purposes of this description is shown in the form of an electric bell. The reference character 3S designates a wayside signal located at the entrance end 3 of section 3-4 for governing railway traffic in the section. Signal 3S may take any suitable form and is shown, for example, as a color light signal comprising a green lamp G, a yellow lamp Y and a red lamp R effective when energized to indicate clear, caution, and stop, respectively.

The section of track 3-4 is provided with a signaling system of the coded track circuit type comprising code transmitting means at exit end 4 of the section, code repeating and control means at location 3a, and decoding and control means at the entrance end 3 of the section.

The code transmitting means at section end 4 include a track transformer 4TT, code generators 75CT and 180CT and a selecting relay HR. The code generating means 75CT and 180CT constitute continuously energized devices which operate contacts 75 and 180 alternately into and out of circuit completing positions at the rate of, for example, 75 and 180 times per minute, respectively. The track transformer 4TT has its secondary winding 10 connected across track rails 1 and 1a adjacent to exit end 4 of the section and has its primary winding 11 supplied, from a suitable source conventionally indicated in the drawing by the terminals BX and CX, with alternating current periodically interrupted or coded by contact 75 or 180 of coding device 75CT or 180CT, with the selection between the contacts 75 and 180 being established according as relay HR is released or picked up, respectively. Relay HR is responsive to traffic in the stretch in advance of section 3-4 and may be controlled by such traffic in a manner similar, for example, to the control shown for relay ACDR and described herein-after. The code transmitting means at exit end 4 of the section accordingly operates to supply coded alternating current at the 180 code rate to section 3-4 when relay HR is picked up, and when that relay is released alternating current coded at the 75 rate is supplied to the section.

The coded current supplied to the exit end of section 3-4 is transmitted through the track rails to location 3a when subsection 3a-4 is vacant. At location 3a a track relay ATR is connected to the track rails of subsection 3a-4 through a receiving transformer RT and a full wave rectifier 13 so that each code pulse of alternating current received by transformer RT is rectified into and supplied into relay ATR as a pulse of direct current. As long as subsection 3a-4 is vacant relay ATR is therefore energized and deenergized in step with the on and off intervals of the coded current supplied to the exit end of the section. Relay ATR has associated therewith a decoding transformer ADT, a code detecting relay ACDR, a code generator 75CT and a code repeating relay CTM. Relay ACDR is controlled by relay ATR through the medium of decoding transformer ADT so as to be energized when and only when relay ATR follows coded energy, as explained in Letters Patent of the United States No. 2,237,788, granted to Frank H. Nicholson et al. on April 8, 1941. The code repeating relay CTM is provided with an energizing circuit

extending from one terminal B of a suitable source of current, such as a battery not shown, through front contact 15 of relay ATR, front contact 16 of relay ACDR, and the winding of relay 5 CTM to the other terminal C of the source of current, and relay CTM therefore normally is energized and deenergized in step with the energized and deenergized conditions of relay ATR. Whenever relay ATR ceases to follow code and relay ACDR releases, relay CTM is then energized over a circuit including back contact 16 of relay ACDR and contact 15 of the code generator 75CT. Relay CTM has associated therewith a track battery 18 and a track transformer 19 comprising a secondary winding 20 and a primary winding 21. Each time relay CTM is energized its front contact 17 closes to connect battery 18 through a limiting resistor 18a across the track rails of subsection 3-3a at its exit end, and each time relay CTM is deenergized its back contact 17 closes to connect secondary winding 20 of transformer 19 to the track rails. The primary winding 21 of transformer 19 is normally deenergized but at times is supplied with alternating current over a circuit extending from terminal BX through front contact 22 of relay ACDR, back contact 23 of a relay CLR, and the primary winding 21 to terminal CX. The relay CLR is controlled by a line circuit in a manner that will be explained herein-after, but at this time it should be noted that relay CLR also controls crossing signal XS over an obvious energizing circuit including back contact 24 of relay CLR.

A code pulse of direct current is supplied to the 35 rails of subsection 3-3a each time contact 17 of relay CTM closes in its front position to connect battery 18 across the track rails, and when subsection 3-3a is vacant these pulses of coded direct current are transmitted through the track rails to the entrance end 3 where a direct current track relay is connected across the rails. Under these conditions, relay TR is energized and deenergized in step with the supply and interruption of current from battery 18 at the opposite 40 end of the subsection. Relay TR has associated therewith a decoding transformer DT, a code detecting relay CDR, and a code rate responsive relay DR. The code detecting relay CDR is controlled by relay TR through the medium of decoding transformer DT in a manner corresponding to the control of relay ACDR by relay ATR, so that relay CDR is energized whenever relay TR follows coded current and is deenergized whenever relay TR ceases to follow coded current. 45 The code rate responsive relay DR is connected to decoding transformer DT in the usual manner through a decoding unit 180DU arranged and proportioned so that relay DR is effectively energized and picked up only when relay TR operates 50 at the 180 code rate. The energization of relay DR therefore is effective to detect operation of relay TR at the 180 code rate.

The reference characters 30 and 31 designate line wires which extend from the entrance end 65 3 of the section to the intersection of highway H with the stretch of track. A line battery 32, a line relay ELR, a decoding transformer EDT and a line controlled relay HLR are located at one end of the line wires, while a line battery 33, 70 line relay ALR, decoding transformer LDT and the previously mentioned line controlled relay CLR are located at the opposite end of the line wires. The line wires 30 and 31 are utilized to control the line controlled relays HLR and CLR, 75 in a manner to be explained in detail herein-

after. Relay HLR cooperates with relay DR to control wayside signal 3S in a manner such that when relay DR is picked up, lamp G of that signal is energized over an obvious circuit including front contact 35 of relay DR; when relay DR is released and relay HLR is picked up, lamp Y of signal 3S is energized over back contact 35 of relay DR and front contact 36 of relay HLR; and when relays DR and HLR are released lamp R is energized over a circuit including back contacts 35 and 36 of relays DR and HLR, respectively. Code generators 75CT and 180CT are provided at entrance end 3, and relay HLR cooperates with these generators and with relays DR and CDR in the control of the coded energy supplied through a track transformer 3TT to the rails of the stretch in the rear of section 3-4. When relay DR is picked up, secondary winding 11 of transformer 3TT is supplied with 180 code current over a circuit extending from terminal BX through contact 180 of code generating device 180CT, front contact 37 of relay CDR, front contact 38 of relay DR and winding 11 of transformer 3TT to terminal CX. When relay DR is released and relay HLR is picked up, 180 code current is supplied to the transformer over a circuit extending from terminal BX through contact 180 of code generating device 180CT, front contact 37 of relay CDR, front contact 39 of relay HLR, back contact 38 of relay DR and winding 11 of transformer 3TT to terminal CX. When both relays DR and HLR are released, 75 code current is supplied to the transformer from terminal BX over contact 75 of coder 75CT, back contact 39 of relay HLR, back contact 38 of relay DR and winding 11 of terminal CX.

The apparatus embodying my invention is in its normal condition when section 3-4 is vacant and relay HR controlled by traffic in the stretch in advance of section 3-4, is picked up. Under these conditions 180 code current is supplied to the track rails at the exit end of section 3-4 and causes operation of relay ATR at a corresponding rate to pick up relay ACDR and operate code repeating relay CTM at a rate corresponding to the rate of operation of relay ATR. Operation of relay CTM by relay ATR results in the application of 180 code direct current to the rails at the exit end of subsection 3-3a to operate relay TR at a corresponding rate and cause relays CDR and DR at the entrance end of the section to be picked up so that lamp G of signal 3S is lighted, and 180 code current is supplied to the section in the rear of section 3-4. Each time that relay CTM is picked up to apply an impulse of direct current to the track rails and in turn energize relay TR, a line circuit involving the line wires 30 and 31 is established for relay ALR and may be traced from one terminal of line battery 32 at the entrance end of the section through front contact 40 of relay TR, front contact 41 of relay CDR, line wire 30, front contact 42 of relay CTM, the winding of relay ALR, front contact 43 of relay CTM, line wire 31, front contact 44 of relay CDR, and front contact 45 of relay TR to the other terminal of battery 32. When relay CTM is deenergized and opens its front contact 47 to disconnect battery 18 from subsection 3-3a, relay TR becomes deenergized and line relay ELR at the entrance end of the section is energized over a line circuit extending from one terminal of battery 33 located at the intersection, through front contact 46 of relay ACDR, back contact 42 of relay CTM, line wire 30, front contact 41 of relay CDR, back contact

40 of relay TR, the winding of relay ELR, back contact 45 of relay TR, front contact 44 of relay CDR, line wire 31, back contact 43 of relay CTM, and front contact 47 of relay ACDR to the other terminal of line battery 33. It follows that with subsection 3-3a vacant, line relay ALR at the intersection is supplied with a pulse of current from battery 32 over the line wires 30 and 31 each time that relays CTM and TR close their front contacts in synchronism, and that relay ELR at the entrance end is energized with a pulse of current supplied from battery 33 over line wires 30 and 31 each time that relays CTM and TR close their back contacts in synchronism. The synchronous operation of the contacts of relays CTM and TR therefore enables the line wires 30 and 31 to provide two separate control channels for controlling line relays ALR and ELR located respectively at the opposite ends of subsection 3-3a. The intermittent energization of relay ALR over the line circuit just described is detected by line controlled relay CLR through the medium of decoding transformer LDT in the manner previously discussed, and relay CLR therefore is energized and picked up whenever relay ALR is recurrently energized over the line circuit. The recurrent energization of relay ELR at the entrance end of the section is similarly detected by relay HLR through the medium of decoding transformer EDT. Under the conditions assumed, that is, with relay CLR energized because of the intermittent energization of line relay ALR, crossing signal XS is deenergized.

When a train operating in the normal direction of traffic in the stretch enters section 3-4, the pulses of energy supplied from battery 18 through contact 47 of relay CTM to the rails of subsection 3-3a are shunted away from relay TR and as a result relays CDR and DR release. The release of relay CDR results in the opening of the line circuits previously traced for relays ELR and ALR, and those relays are steadily deenergized. The cessation of code operation of relay ELR is detected by relay HLR, which releases and as a result lamp G becomes dark while lamp R becomes energized over its previously traced circuit to cause signal 3S to display its stop aspect. The track circuit current supplied to the rails of the stretch in the rear of section 3-4 is shifted to the 75 code rate by the release of relay HLR which completes the circuit for transformer 3TT previously mentioned including contact 75 of coder 75CT and back contacts 39 and 38 of relays HLR and DR, respectively. Line controlled relay CLR at the exit end of subsection 3-3a also releases due to the cessation of code operation of relay ALR and as a result back contact 24 of relay CLR closes to complete the obvious energizing circuit for crossing signals XS, thereby initiating operation of that signal to provide a warning to highway users of the approach of a train to the crossing. The release of relay CLR also results in the supply of alternating current to primary winding 21 of transformer 19 over the previously traced circuit including back contact 23 of relay CLR and front contact 22 of relay ACDR, and as a result each time that back contact 47 of relay CTM is closed a pulse of alternating current is applied to the track rails. These pulses of coded alternating current in the rails of the subsection may be utilized in the customary manner to control train carried apparatus on the train occupying subsection 3-3a.

When the train enters advance subsection

3a-4 the coded alternating current supplied to exit end 4 of the section is shunted away from relay ATR so that relay ACDR releases to open its front contact 22 and deenergize primary winding 21 of transformer 19, thereby terminating the application of coded alternating current to the rails of subsection 3-3a. Contact 16 of relay ACDR also operates from its front to its back position to shift the energization of relay CTM from contact 15 of relay ATR to contact 15 of code generating device 15CT, and as a result relay CTM operates at the 75 code rate to apply direct current pulses from battery 18 to the track rails at the corresponding rate. When the train vacates subsection 3-3a, the pulses of current coded at the 75 rate applied at exit end 3a operate track relay TR, and relay CDR is thereupon picked up to close its contacts 41 and 44 in the circuit of relay ALR. The contacts of relays TR and CTM operate in synchronism to alternately complete and interrupt the circuit of relay ALR at the rate of 75 times per minute, and this operation is detected by relay CLR which picks up to open its back contact 24 and thereby deenergize crossing signals XS, and to open its back contact 23 in the energizing circuit of primary winding 21 of transformer 19. At this time contacts 46 and 47 of relay ACDR are held open so that the synchronous operation of relays TR and CTM does not result in energization of line relay ELR at the entrance end of the section and no change is effected at this time in the condition of line controlled relay HLR. The train in vacating subsection 3-3a therefore causes the apparatus embodying my invention to supply the track rails with coded direct current which is utilized to detect the vacant condition of the section and which causes termination of the operation of the crossing signal but does not alter the control of wayside signal 3S at the entrance end of the section.

When the train vacates section 3-4 and occupies the stretch in advance of that section, relay HR will be released as is customary in railway signaling practice so that its back contact 12 completes the circuit over which 75 code current is selected for application to the rails of section 3-4. Relay ATR responds to this 75 code current and picks up code detecting relay ACDR which operates its contact 16 from its back position to its front position to shift the energization of relay CTM back to control by contact 15 of relay ATR. Relay CTM accordingly continues to operate at the 75 code rate in step with the energization of relay ATR and no change is effected in the operation of the decoding apparatus associated with relay TR at the entrance end of the section. However, contacts 46 and 47 of relay ACDR close so that line relay ELR at the entrance end of the section is energized each time that relays TR and CTM close their back contacts in synchronism. The coded operation of relay ELR is detected by relay HLR which picks up to deenergize lamp R and energize lamp Y of signal 3S over its circuit including back contact 35 of relay DR and front contact 36 of relay HLR. Also, the previously traced circuit including back contact 38 of relay DR and front contact 39 of relay HLR is completed over which 180 code current is supplied to track transformer 3TT for the stretch in the rear of section 3-4.

When relay HR is picked up in response to traffic conditions in the stretch in advance of section 3-4, front contact 12 of that relay closes to complete the circuit over which 180 code current is supplied to secondary winding 11 of track

transformer 4TT, and as a result the coded current supplied to exit end 4 of section 3-4 is shifted to the 180 code rate and causes relays ATR, CTM and TR to operate at corresponding rates. Relay DR associated with relay TR thereupon becomes energized and picks up to close its front contact 35 to complete the obvious energizing circuit for lamp G of signal 3S; and its front contact 38 to complete the circuit over which 180 code normally is supplied to track transformer 3TT. The apparatus is therefore restored to its normal condition as represented in the drawing.

It is to be noted that in this normal condition of the apparatus, subsection 3-3a which constitutes a control section for signal XS is supplied with code pulses of direct current. When the control section is occupied by a train the supply of code pulses of direct current is maintained while at the same time a code pulse of alternating current is supplied to the track rails during each off period of the direct current code. These pulses of alternating current are of the type which may be utilized in the customary manner to control apparatus carried on a train occupying the control section. The other section 3a-4 is normally supplied with coded alternating current which, of course, is effective to control train carried apparatus and the system organization is thus such that the complete section 3-4 is supplied with pulses of alternating current whenever such supply is necessary for the control of train carried apparatus on a train occupying the section. After a train vacates the control section the pulses of alternating current are removed from the track rails and the vacant condition of the control section is detected by coded pulses of direct current which operate wayside apparatus and are detected by a code detecting relay utilized to establish control of the highway crossing signal, but no control is effected by this apparatus over the wayside signals governing traffic in the section. Also, should a second train follow the first into section 3-4, the coded track circuit current applied to the control section while the first train occupies the remaining part of section 3-4 is not of the type effective to operate train carried apparatus so that the train carried apparatus on the second train will be conditioned to indicate the occupied condition of the entire section.

It follows that apparatus embodying my invention is arranged and organized in such a manner as to make use of coded direct current track circuit energy for detecting the clearing of an approach section for a crossing signal in a stretch of track equipped with a railway signaling system which provides for the control of either or both wayside signals and train carried cab signals, and the arrangement is such as not to interfere with the proper operation of cab signal or train control apparatus on trains operating in the stretch of track. The benefits that follow from the use of coded track circuit energy in a system of railway signaling are therefore obtained by means which provide for the proper control of highway crossing signals and train carried cab signals in coded track circuit systems of railway signaling.

Although I have herein shown and described only one form of railway signaling apparatus embodying my invention, it is to be understood that various changes and modifications may be made therein within the scope of the appended

claims without departing from the spirit and scope of my invention.

Having thus described my invention, what I claim is:

1. In a coded track circuit system of railway signaling for a stretch of railway track in which traffic normally operates in a given direction, in combination, a section of railway track in said stretch, a track relay at the entering end and a track battery at the exit end of said section, a contact operable between a first and second position, means for operating said contact alternately between said positions, a circuit completed in the first position of said contact for connecting said track battery to the rails at said exit end of said section for operating said track relay alternately between a first and a second position in synchronism with the operation of said contact when said section is vacant, two line wires extending between the ends of said section, a first battery and a first relay at said entering end of said section and a second battery and a second relay at said exit end of said section, means governed by traffic in said section for connecting said first battery in circuit with said second relay over said two line wires when said track relay and said contact are in corresponding first positions, means governed by traffic in said stretch in advance of said section for connecting said second battery in circuit with said first relay over said two line wires when said track relay and said contact are in corresponding second positions, and traffic governing means controlled by said first and second relays.

2. In a coded track circuit system of railway signaling for a stretch of railway track in which traffic normally operates in a given direction, in combination, a section of railway track in said stretch, a track relay at the entering end and a code transmitting relay at the opposite end of said section, means for operating said code transmitting relay alternately between a first and second position at a rate dependent upon traffic conditions in the stretch in advance of said section, means controlled by said code transmitting relay for alternately energizing and deenergizing the track rails of said section in step with the operation of said code transmitting relay for operating said track relay alternately between a first and second position in synchronism with said code transmitting relay when said section is vacant, two line wires extending between the ends of said section, a first battery and a first relay at the entering end of said section and a second battery and a second relay at the opposite end of said section, means governed by traffic in said section for connecting said first battery in circuit with said second relay over said two line wires when said track relay and said code transmitting relay are in corresponding first positions, and means governed by traffic in said stretch in advance of said section for connecting said second battery in circuit with said first relay over said two line wires when said track relay and said code transmitting relay are in corresponding second positions.

3. In a coded track circuit system of railway signaling for a stretch of railway track in which traffic normally operates in a given direction, in combination, a section of railway track in said stretch, a track relay at the entering end and a track battery at the exit end of said section, a contact operable between a first and a second position, means for applying coded energy to the rails of said stretch at a point in advance of said

section, means controlled by said coded energy when said stretch between said section and said point is vacant for operating said contact alternately between said positions in step with said coded energy, means at said exit section end for operating said contact alternately between said positions at a given rate when traffic occupies said stretch between said section and said advance point, a circuit completed by said contact in its said first position for connecting said track battery to the rails at said exit end of said section effective when said section is vacant for operating said track relay in synchronism with the operation of said contact, two line wires extending between the ends of said section, means controlled in synchronism by said contact and by said track relay for providing two separate control channels over said two line wires, means governed by traffic in said stretch in advance of said section for controlling one of said two control channels, and means at the entering end of said section controlled by said one control channel and means at the exit end of said section controlled by the other of said control channels.

25 4. In combination with a stretch of railway track in which traffic equipped with train carried signaling facilities normally operates in a given direction and including a track section, a track relay at the entering end and a track battery and a track transformer at the opposite end of said section, a contact operable between a first and a second position, means for applying coded energy to the rails of said stretch at a point in advance of said section, means controlled by said coded energy when said stretch between said section and said advance point is vacant for operating said contact alternately between said positions in step with said coded energy, means at said opposite section end for operating said contact alternately between said positions at a given rate when traffic occupies said stretch between said section and said given point, a circuit completed by said contact in its said first position effective when said section is vacant for connecting said track battery to the rails at said opposite end of said section for operating said track relay in synchronism with the operation of said contact, a circuit completed in said second position of said contact for connecting a secondary winding of said track transformer to the rails at said opposite end of said section, two line wires extending between the ends of said section, a first battery and a first relay at said entering end of said section and a second battery and a second relay at said opposite end of said section, means governed by traffic in said section for connecting said first battery in circuit with said second relay over said two line wires when said track relay and said contact are in corresponding first positions, means governed by traffic in said stretch in advance of said section for connecting said second battery in circuit with said first relay over said two line wires when said track relay and said contact are in corresponding second positions, means at the entering end of said section controlled by said first relay for governing traffic in said section, and means at said opposite end of said section controlled by said second relay for energizing the primary winding of said track transformer.

50 5. In combination with a stretch of railway track in which traffic normally operates in a given direction and including a section of railway track intersected by a highway at its exit end, a highway crossing signal at said intersec-

11

tion, a track relay at the entering end and a track battery at the opposite end of said section, a contact operable between a first and a second position, means for continuously operating said contact alternately between said positions, a circuit completed in the first position of said contact for connecting said track battery to the rails of said section for operating said track relay alternately between a first and a second position in synchronism with the operation of said contact when said section is vacant, two line wires extending between the ends of said section, a first battery and a first relay at said entering end of said section and a second battery and a second relay at said opposite end of said section, means governed by traffic in said section for connecting said first battery in circuit with said second relay over said two line wires when said track relay and said contact are in corresponding first positions, means governed by traffic in said stretch in advance of said section for connecting said second battery in circuit with said first relay over said two line wires when said track relay and said contact are in corresponding second positions, railway traffic governing means at the entering end of said section controlled by said first relay, and means at said opposite end of said section controlled by said second relay for operating said highway crossing signal.

6. In a coded track circuit system of railway signaling for a stretch of railway track in which traffic equipped with train carried cab signaling facilities normally operates in a given direction, in combination, a section of railway track in said stretch intersected by a highway at its exit end, a highway crossing signal at said intersection, a track relay at the entering end and a track battery and a track transformer at said exit end of said section, a contact operable between a first and a second position, means for continuously operating said contact alternately between said positions at a rate dependent upon traffic conditions in said stretch in advance of said section, a circuit completed in the first position of said contact for connecting said track battery to the rails at said exit end of said section for operating said track relay alternately between a first and a second position in synchronism with the operation of said contact when said section is vacant, a circuit completed in said second position of said contact for connecting a secondary winding of said track transformer to the rails at said exit end of said section, two line wires extending between the ends of said section, a first battery and a first relay at said entering end of said section and a second battery and a second relay at said exit end of said section, means governed by traffic in said section for connecting said first battery in circuit with said second relay over said two line wires when said track relay and said code transmitting relay are in corresponding first positions, means governed by traffic in said stretch in advance of said section for connecting said second battery in circuit with said first relay over said two line wires when said track relay and said code transmitting relay are in corresponding second positions, means at the entering end of said section controlled by said first relay for governing traffic in said stretch in the rear of said section, and means at said exit end of said section controlled by said second relay for controlling said highway crossing signal and for energizing the primary winding of said track transformer.

12

7. In combination with a stretch of railway track in which traffic equipped with train carried cab signal facilities normally operates in a given direction and including a track section intersected by a highway at its exit end, a highway crossing signal at said intersection, a track relay at the entering end and a track battery and a track transformer at said exit end of said section, a contact operable between a first and a second position, means for applying coded energy to the rails of said stretch at a point in advance of said section, means controlled by said coded energy when said stretch between said section and said point is vacant for operating said contact alternately between said positions in step with said coded energy, means at said exit section end for operating said contact alternately between said positions at a given rate when traffic occupies said stretch between said section and said advance point, a circuit completed by said contact in its said first position for connecting said track battery to the rails at the exit end of said section effective when said section is vacant for operating said track relay in synchronism with the operation of said contact, a circuit completed in said second position of said contact for connecting a secondary winding of said track transformer to the rails at said exit end of said section, two line wires extending between the ends of said section, a first battery and a first relay at said entering end of said section and a second battery and a second relay at said exit end of said section, means governed by traffic in said section for completing a circuit including said first battery and said second relay and said two line wires when said track relay and said contact are in corresponding first positions, means governed by traffic in said stretch in advance of said section for completing a circuit including said second battery and said first relay and said two line wires when said track relay and said contact are in corresponding second positions, means for governing traffic in said stretch in the rear of said section controlled by said first relay, and means controlled by said second relay for controlling the operation of said highway crossing signal and for energizing the primary winding of said track transformer by alternating current.
8. In combination with a stretch of railway track in which traffic equipped with train carried facilities responsive to coded pulses of alternating current in the track rails normally operates in a given direction, said stretch including an insulated track section provided at its entering end with a wayside railway traffic controlling signal and divided by insulating joints into adjoining rear and advance subsections, said rear subsection intersected by a highway at its exit end and provided with a highway crossing signal at such intersection, means for applying to the track rails at the exit end of said advance subsection alternating current coded at one or another of a plurality of rates dependent upon traffic conditions in said stretch in advance of said section, a code transmitting device for operating contacts between a first and a second position, means controlled by traffic in said advance subsection for causing said code transmitting device to operate its contacts alternately between said first and second positions at a rate corresponding to the code rate of energy in the rails of said advance subsection, means operative when said advance subsection is occupied for causing said code transmitting device to operate its contacts at a given code

rate, a track battery and a track transformer, means controlled by said code transmitting device according as said contacts are in said first or said second position for respectively connecting said battery or the secondary winding of said track transformer to the rails at the exit end of said rear subsection, a direct current code responsive relay connected to the rails at the entering end of said rear subsection and having contacts operable between a first and second position according as said track relay is energized or deenergized respectively, two line wires extending between the ends of said rear subsection, a first line battery and first line relay at the entering end and a second line battery and second line relay at the exit end of said rear subsection, a circuit including first position contacts of said track relay and said code transmitting device for synchronously connecting said first line battery and said second line relay to said line wires, a circuit controlled by traffic conditions in the entire track section and including second position contacts of said track relay and said code transmitting device for synchronously connecting said second line battery and said first line relay to said line wires, means controlled by said first line relay for governing said wayside signal, and means controlled by said second line relay for controlling the operation of said highway crossing signal and the supply of alternating current to the primary winding of said track transformer.

9. In combination with a stretch of railway track in which traffic equipped with train carried facilities responsive to coded pulses of alternating current in the track rails normally operates in a given direction, said stretch including an insulated track section divided by insulating joints into adjoining rear and advance subsections and provided at its entering end with code transmitting means for supplying the rails of the stretch in the rear of said section with energy coded at one or another of a plurality of code rates depending on traffic conditions in said section, said rear subsection intersected by a highway at its exit end and provided with a highway crossing signal at such intersection, means for applying to the track rails at the exit end of said advance subsection alternating current coded at one or another of a plurality of rates dependent upon traffic conditions in said stretch in advance of said section, a code transmitting device for op-

erating contacts between a first and a second position, means controlled by traffic in said advance subsection for causing said code transmitting device to operate its contacts alternately between said first and second positions at a rate corresponding to the code rate of energy in the rails of said advance subsection, means operative when said advance subsection is occupied for causing said code transmitting device to operate its contacts at a given code rate, a track battery and a track transformer, means controlled by said code transmitting device according as said contacts are in said first or said second position for respectively connecting said battery or the secondary winding of said track transformer to the rails at the exit end of said rear subsection, a direct current code responsive relay connected to the rails at the entering end of said rear subsection and having contacts operable between a first and second position according as said track relay is energized or deenergized respectively, two line wires extending between the ends of said rear subsection, a first line battery and first line relay at the entering end and a second line battery and second line relay at the exit end of said rear subsection, a circuit including first position contacts of said track relay and said code transmitting device for synchronously connecting said first line battery and said second line relay to said line wires, a circuit controlled by traffic conditions in the entire track section and including second position contacts of said track relay and said code transmitting device for synchronously connecting said second line battery and said first line relay to said line wires, means controlled by said first line relay for governing said code transmitting means for the rails in the rear of said section, and means controlled by said second line relay for controlling the operation of said highway crossing signal and the supply of alternating current to the primary winding of said track transformer.
